(57) CLAIM

The ornamental design for a lounge chair, as shown and described.

DESCRIPTION

FIG. 1 is a front perspective view of a lounge chair showing my new design;

FIG. 2 is a front elevation view thereof;

FIG. 3 is a left side elevation view, the opposite side being a mirror image thereof;

FIG. 4 is a rear elevation view thereof; and,

FIG. 5 is a top plan view thereof.

The dash-dash lines in the FIGS. 1-5 represent environmental elements that form no part of the claimed design.

1 Claim, 5 Drawing Sheets

FIG. 1

FIG. 2

FIG. 3

FIG. 4

FIG. 5
